Hamilton Sanders LLP

(57) **CLAIM**

The ornamental design for an outdoor fountain, substantially as shown and described.

DESCRIPTION

FIG. 1 is a front-right side perspective view of an outdoor fountain.

FIG. 2 is a front view of the outdoor fountain of FIG. 1.

FIG. 3 is a right-side view of the outdoor fountain of FIG. 1.

FIG. 4 is a left-side view of the outdoor fountain of FIG. 1.

FIG. 5 is a rear view of the outdoor fountain of FIG. 1.

FIG. 6 is a top view of the outdoor fountain of FIG. 1; and, FIG. 7 is a bottom view of the outdoor fountain of FIG. 1. The broken lines and all areas within them depict portions of the outdoor fountain that form no part of the claim.

1 Claim, 7 Drawing Sheets
